UNITED STATES PATENT OFFICE.

ARTHUR E. ANAKIN AND WILLIAM J. SHEALY, OF SALT LAKE CITY, UTAH.

AUXILIARY SAFE-LOCK.

1,021,651.

Specification of Letters Patent. Patented Mar. 26, 1912.

Application filed November 22, 1911. Serial No. 661,790.

To all whom it may concern:

Be it known that we, ARTHUR E. ANAKIN and WILLIAM J. SHEALY, citizens of the United States, residing at Salt Lake City, 5 in the county of Salt Lake and State of Utah, have invented certain new and useful Improvements in Auxiliary Safe-Locks, of which the following is a specification.

This invention relates to an improved auxiliary locking means designed especially for use in connection with the ordinary locking mechanism of safes or vaults, and of the type set forth in the application filed by Arthur E. Anakin, on August 25, 1911, Serial Number 654,964.

The auxiliary locking means hereinafter more fully described has been devised with a view of simplifying the same to the greatest extent possible in the use of a minimum 20 number of parts, each of which is constructed so as to be readily manufactured at a nominal cost.

A further object of the invention has been to produce an auxiliary locking device of 25 the class referred to which, by reason of the adjustability of certain parts, and interchangeable mounting of a locking member, permits of application of the invention to a safe door to operate vertically or horizontally, as may be desired and most convenient in view of the location of the permutation lock commonly employed on safe or vault doors.

The invention also consists in the employment in the above mechanism of a flexible operating member adapted to be directly actuated to cause operation of the auxiliary locking means in the event the main safe lock is tampered with, as in an attempt to 30 burglarize, or otherwise obtain unauthorized access to the interior of the safe when closed.

For a full understanding of the present invention, reference is to be had to the following description and to the accompanying drawings, in which—

Figure 1 is a fragmentary vertical sectional view showing the invention applied to the door of the safe, ready for use. Fig. 50 2 is a transverse sectional view looking toward the auxiliary locking means from the inside of the safe. Figs. 3 and 4 are side and edge views respectively, of the locking member. Fig. 5 is a side view of the tubu-

lar supporting member, locking bolt, and associated parts. Figs. 6 and 7 are side and edge views of the supporting arm for the locking member. Fig. 8 is a sectional view showing a different adjustment of the parts of the auxiliary locking means. Fig. 9 is 60 an end view of the parts shown in Fig. 8.

Throughout the following detail description and on the several figures of the drawings, similar parts are referred to by like reference characters.

The general operation of the auxiliary locking means of this invention, as well as certain analogous features of construction, are presented in the previous application above referred to and comprise, in combination, the usual safe designated A provided with a door of any conventional type carrying the combination lock mechanism shown at B, the latter being conventionally illustrated also. On the door C, as shown in 65 Figs. 1 and 2, is mounted a tubular supporting member 1, arranged vertically and having one end threaded and screwed into an opening in the upper end portion of the door, or otherwise attached, the threaded 70 portion of the part being designated 16.

In the member 1 is arranged a locking bolt 2 normally adapted to be projected at one end from the supporting member 1 by means of a spring 3 into engagement with 75 a locking recess 15 in a wall of the safe. The tubular member 1 is formed with a slot 4 intermediate its ends and a locking member 5 comprising an angle lever is pivoted at 80 6 upon an arm 11 carried by the member 1. The arm 11 has an opening 13 to receive the member 1. A set screw 6* is used to attach the arm 11 adjustably to the supporting member 1.

The locking member 5, when arranged in 85 the position shown in Figs. 1 and 2, has a lateral projection 9 to enter the slot 4 and engage with a recess 2* in the locking bolt 2 to normally hold said bolt retracted in the member 1.

The projection 9 is carried by one arm of the locking member 5 and the other arm of said member has a flexible connection 7 attached thereto at 10, said connection extending in rear of the tumbler casing of the 90 combination lock B, and being secured at 8 to the door C of the safe.

The arrangement of the parts as above de-

scribed, is such that normally the auxiliary locking means is inactive so that the safe door C may be opened at will, without interference on the part of the said locking means. However, should an attempt be made to gain unauthorized access to the safe when locked by the main locking mechanism, inward movement of the parts of the combination lock B will cause engagement 10 thereof with the connection 7 in such a way as to exert a pull on said connection, tripping the locking member 5, disengaging the part 9 from the bolt 2, and permitting the latter to enter the recess 15 and thus lock 15 the safe door closed independently of the main locking mechanism. The liability of unauthorized opening of the safe is eliminated in the above manner.

The arrangement of the parts shown in 20 Figs. 8 and 9 is sometimes desirable and especially when the locking bolt 2 is to operate horizontally on the door C. When the latter arrangement of parts is employed, the locking member 5, instead of being pivoted 25 to the arm 11 by the pivot screw 6 entering the opening 14, will be arranged for movement in a plane parallel with that including the arm 11, by mounting the pivot 6 transversely on the arm, screwing the pivot into 30 the opening 12. The openings 12 and 14 are shown clearly in Fig. 7 in their relative positions.

In the modified adjustment of the parts, the projection 9 becomes inoperative because 35 the longer arm of the locking member 5 engages directly with the bolt 2, such engagement being afforded by movement of the arm 11 toward the center portion of the supporting member 1 and securing said arm at 40 the said adjustment by the set screw 6^a before mentioned.

From the foregoing, it will be apparent that the locking member 5 is adapted for interchangeable mounting of the member 1 45 to operate in a plane at substantially a right angle to that of the arm 11, or in a plane parallel with the arm 11, according to whether a vertical or horizontal movement of the locking bolt is required or desired. 50 The adjustment of the locking member 5 is necessary in order to bring the same into a proper position for actuation by the connection 7 that cooperates with the main locking mechanism of the safe. One end of the 55 spring 3 bears against a plug 17, or other stop at the free extremity of the supporting member 1.

It will be understood that the term "safe," as used herein, contemplates structures such 60 as vaults and equivalents.

Having thus described the invention, what is claimed as new is:

1. In combination, a safe comprising main locking mechanism and a door, auxiliary

locking mechanism consisting of a supporting member mounted on the door, a locking bolt carried by said supporting member to engage a wall of the safe, a locking member normally holding said bolt in an inactive position, means for projecting the bolt into a locking position when released from the locking member, means operable on tampering with the main locking mechanism of the safe for actuating the locking member, and means for interchangeably connecting the locking member with the supporting member to permit of mounting the locking member for movement in different positions in relation to the locking bolt.

2. In combination, a safe comprising main locking mechanism and a door, auxiliary locking mechanism consisting of a supporting member mounted on the door, a locking bolt carried by said supporting member to engage a wall of the safe, a locking member normally holding said bolt in an inactive position, means for projecting the bolt into a locking position when released from the locking member, means operable on tampering with the main locking mechanism of the safe for actuating the locking member, an arm carried by the supporting member, and means for connecting the locking member to said arm at different points on the body of the latter, whereby the locking member may be arranged in different positions for cooperation with the locking bolt.

3. In combination, a safe comprising main locking mechanism and a door, auxiliary locking mechanism consisting of a supporting member mounted on the door, a locking bolt carried by said supporting member to engage a wall of the safe, a locking member normally holding said bolt in an inactive position, means for projecting the bolt into a locking position when released from the locking member, means operable on tampering with the main locking mechanism of the safe for actuating the locking member, an arm, means adjustably connecting said arm with the supporting member, and means adjustably connecting the locking member to the arm whereby the locking member and arm may be adjusted to occupy positions permitting cooperation of the locking member and locking bolt when the auxiliary mechanism is arranged in different positions on the safe door.

4. As an article of manufacture, an auxiliary locking device consisting of a tubular supporting member, an arm adjustable longitudinally of the supporting member, a locking bolt mounted for movement in the supporting member, a locking member, and fastening means for securing the locking member in positions on the arm in which the locking member operates in a plane transverse to or parallel with the arm.

5. In combination, a safe comprising a door having a main locking mechanism therefor, inactive auxiliary locking means for said safe arranged to coöperate with the door to lock the same closed independently of the main locking mechanism, and a flexible connection secured to the auxiliary locking means at one end and extending across the main locking mechanism in the path of 10 abnormal movement thereof, said connection being permanently connected at its opposite end to the door aforesaid.

In testimony whereof we affix our signatures in presence of two witnesses.
